UNITED STATES PATENT OFFICE.

HENRY HOHMAN, OF STOCKTON, CALIFORNIA.

DREDGER.

1,356,624.

Specification of Letters Patent. Patented Oct. 26, 1920.

Application filed January 19, 1920. Serial No. 352,312.

To all whom it may concern:

Be it known that I, HENRY HOHMAN, a citizen of the United States, residing at Stockton, in the county of San Joaquin, State of California, have invented certain new and useful Improvements in Dredgers; and I do declare the following to be a full, clear, and exact description of the same, reference being had to the accompanying drawings, and to the characters of reference marked thereon, which form a part of this application.

This invention relates to improvements in dredgers and particularly to the endless chain and bucket type used for mining and channel dredging purposes.

The principal object of the invention is to so arrange the chain and buckets that the bank from which the dirt is being removed will be free from the tendency to cave in which is a common source of annoyance with the use of the ordinary bucket dredger, which digs entirely under water and undermines the bank.

Another object is to position the bucket mechanism relative to the hull of the dredger so that the latter will always remain substantially on an even keel.

A third object is to run the chain on ball bearings at that part having the working strain and weight thereon, these balls being so mounted that there is very little likelihood of their sticking or otherwise refusing to function under working conditions and with which the chain will be subject to very little frictional wear.

A further object of the invention is to produce a simple and inexpensive device, and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a side elevation of the dredger, the hull being partly broken off at one end.

Fig. 2 is an enlarged fragmentary longitudinal section showing the chain supporting ball arrangement.

Fig. 3 is an enlarged fragmentary cross section taken on a line 3—3 of Fig. 1.

Referring now more particularly to the

characters of reference on the drawings, the numeral 1 denotes a floatable hull whose keel or under side at one end forms an enlarged circle as at 2 depending for some distance below the normal keel level 1^a and also projecting above the water level for a considerable distance as at 3.

This circular portion is so designed relative to the hull that the center of radius of curvature is some distance above the water line, as at "A".

Transversely spaced channels 4 are secured around this circular portion and extend up therebeyond at the outer or high end at a tangential angle thereto to a point a suitable distance above the hull, terminating adjacent polygonal sided tumblers 5 mounted in a supporting framework 6 carried by the hull.

The tumblers are in vertical alinement with the channels 4, and are driven by any suitable means such as a chain drive 7 from a power plant carried by the hull inside the deck house 8.

Over the tumblers and around the channels 4 run endless chains 9, each link of which has a length equal to the length of one side of the tumblers. This construction, as will be evident, permits the chains to be positively driven, and does away with the usual sprocket wheel and its attendant frictional wearing contact with the chain. It also enables me to use plain pieces of metal for the links, instead of hollow or double members with rollers, etc., to engage the sprockets, which are subject to rapid wear under the abrasive effects of dirt and grit.

These chains run in the channels 4 and are guided by the sides thereof, while carried in the channels between the bottom of the same and the under sides of the chains are balls 10, adapted for limited rolling movement longitudinally of the channels, being held in such limits by stops 11 secured to or bent up from the bottom of the channels.

Buckets 12 are secured to the alternate links of the chains, and hold the chains together as a unit.

These buckets of course have one end open to adapt them to cut the bank 13 on the upward movement of the chains around the outer end of the hull portion 2, and are adapted to discharge into a flume 14 carried by the hull and sloping downwardly from the opposite side of the tumblers 5.

A well 15 is of course provided in the hull to enable the buckets and chains to pass therethrough to engage the channels at the inception of the circular portion 2 of the hull.

In operation, the strain of digging the weight of the load dug is carried by the balls 10.

When a link having a loaded bucket thereon is passing over the balls, the latter roll in the channel to the upper stop 11 therefor. When a light or idle link passes thereby, the strain is removed from the ball, and the latter then works back to its normal position against its lower stop, ready for the next loaded link.

The balls having considerable freedom of movement, precludes the possibility of any of them becoming clogged and inactive, and insures that the chain will always have a comparatively frictionless rolling contact therewith rather than a sliding or rubbing contact, thus insuring longevity of the parts.

The relatively great diameter of the portion 2 insures that the bank from which the material is being dug will retain a gentle curvature of profile, not apt to cave in.

From the foregoing description it will be readily seen that I have produced such a device as substantially fulfills the object of the invention as set forth herein.

While this specification set forth in detail the present and preferred construction of the device still in practice such deviations from such detail may be resorted to as do not form a departure from the spirit of the invention, as defined by the appended claims.

Having thus described my invention, what I claim as new and useful and desire to secure by Letters Patent is:—

1. A dredger including a water borne hull, a circular portion forming one end thereof extending below the normal keel level of the hull and above the water line, and endless bucket-carrying chains passing around such circular portion.

2. A dredger including a water borne hull, a circular portion on one end thereof extending below the normal keel level of the hull and above the water line, the center of such portion being above the water line, transversely spaced channels around such circular portion, endless bucket-carrying chains guided in such channels, and balls in

the channels bearing against the inner face of the chains, the balls being adapted for limited longitudinal movement in the channels.

3. A dredger including a water borne hull, a circular portion on one end thereof extending below the normal keel level of the hull and above the water line, the center of such portion being above the water line, transversely spaced channels around such circular portion, endless chains guided in the channels, buckets on the alternate ones of the links of the chains, balls in such channels bearing against the inner surface of the chains and stops in the channels between each ball, the latter having longitudinal freedom of movement between the stops.

4. A dredger including a water borne hull, a circular portion forming one end thereof extending below the normal keel-level of the hull and above the water line, the center of such portion being above the water line, transversely spaced channels around such circular portion, and endless digger carrying chains guided in such channels.

5. A dredger including a water borne hull, a circular portion forming one end thereof extending below the normal keel-level of the hull and above the water line, the center of such portion being above the water line, transversely spaced channels around such circular portion, endless digger-carrying chains guided in such channels, and means in the channels for reducing the friction of contact of the chains therewith.

6. A dredger comprising a water-borne hull, endless digger-carrying chains, and guides for said chains projecting downwardly beyond one end of the hull, such guides being substantially circular, and projecting below the normal keel-level of the hull and to a point above the water line.

7. A dredger comprising a water borne hull, endless digger-carrying chains, and guides for said chains projecting downwardly beyond one end of the hull, such guides being substantially circular, and projecting below the normal keel-level of the hull, the center of the circle being above the water line, whereby at one operation the dredger may cut a continuous area from the lowest point of the chains to the top of the guides above the water line.

In testimony whereof I affix my signature.
HENRY HÖHMAN.
